UNITED STATES PATENT OFFICE.

HENRY S. POWELL, OF NEW YORK, N. Y.

WATER-HEATER.

SPECIFICATION forming part of Letters Patent No. 729,793, dated June 2, 1903.

Application filed July 8, 1902. Serial No. 114,734. (No model.)

To all whom it may concern:

Be it known that I, HENRY S. POWELL, a citizen of the United States, residing in the city of New York, county and State of New York, have invented a new and useful Improvement 5 in Water-Heaters, of which the following is a specification.

My invention relates to improvements in water-heaters in which steam-pipes or a steam-coil is mounted within a water receptacle, which receptacle is provided with water inlets and outlets and also with automatic means for regulating the amount of heating fluid which is to pass through the pipes or to shut 15 off said fluid at a given time; and the objects of my invention are, first, to provide an intermittent or continuously-operating water-heater; second, to provide a heater which shall raise the water to any desired temperature 20 during its passage through the heater from the water-main, and third, to provide a device of simple and economical construction. I attain these objects by the mechanism illustrated in the accompanying drawings, in 25 which—

Figure 1 shows an elevation of the heater and its connections. Fig. 2 shows a similar view, partly in section, to illustrate the interior arrangement.

Similar letters refer to similar parts throughout both views.

The water-receptacle proper A is mounted on any suitable base, as A³, and is preferably cylindrical in form, having end plates A' and A² to close either end. The end plate A' may, if desired, be formed integral with the support A³ or as indicated in Fig. 2. Within this receptacle A are mounted the fluid-heating pipes B. These pipes may be arranged 35 in any manner to provide a sufficient heating-surface to accomplish the objects of the device. The form preferred, however, is that shown in Fig. 2, in which headers b' and b² are mounted near each end of the receptacle 40 and have connected therewith the coils B. One of the headers, as b', is connected with the steam-supply pipe B', having a valve D', operated in a manner hereinafter described. The 45 opposite header b² is connected with a steam-exhaust or drip pipe B², which in turn may be connected with a steam-trap E of any well-known construction. The inlet for the water-

supply is preferably arranged as shown, and consists of a water-pipe C, adapted to be connected with any source of water-supply and having a portion c extending substantially the full length of the receptacle to a point near the bottom. The opening for the water-outlet is arranged adjacent the opening for the water-inlet and is fitted with a pipe C'. 55 The base of the receptacle is preferably provided with a drain-pipe a, having a valve a'. Connected with the steam-valve D' of the pipe B' is a thermostat D of any desired form. This thermostat has a part d² projecting into 60 the water-receptacle near the outlet, whereby the temperature of the water at a point adjacent to the outlet C' will determine the volume and pressure of the steam-supply passing through the valve D'. The steam-pipe B' and 65 the water-outlet C' may be provided with indicators x and y, respectively, if desired. Furthermore, the water-pipe C may be provided with a relief-valve z, if desired. The pipe d³, which joins the thermostat D with the valve 70 D', may also be provided with a drip-pipe d', if desired. 75

The operation of the device is as follows: Cold water from the given source is turned into the heater through the pipe C at a point 80 near the bottom. While the receptacle is filling with water steam is admitted to the coils B through the pipe B'. At this time the apparatus is more or less cold, and the thermostat D therefore permits of a maximum 85 volume of steam through the valve D'. When, however, the water reaches the part d² of the thermostat D, the temperature of the water as it rises from the effect of the heat of the steam-coil B will greatly influence the thermostat D to close the valve D', and thereby lessen the amount of steam admitted to the coils until the desired temperature is maintained. The thermostat may be adjusted 90 so as to permit the water to reach any desired temperature before the steam is cut off, and therefore the user of the water may determine the temperature at will in any of the well-known ways of regulating such thermostats. 95

The parts of the device are so proportioned 100 that it is possible to have the water-inlet and water-outlet open to their fullest extent, thus allowing for a continuous steady stream of

hot water. This is accomplished by reason of the diameter of the steam and water pipes and the capacity of the receptacle A.

In the construction illustrated in the drawings the cold-water inlets and the hot-water outlet are large enough for a light pressure. For heavy pressure they can be made smaller. The steam connections are of sufficient size for low-pressure steam. For high pressure they can be reduced in size.

For an average water-supply the following proportions have been found most practicable: diameter of receptacle A, twenty-two inches; height over all, seventy-two inches; capacity in gallons per hour, two thousand five hundred; cold-water inlet, two inches diameter; hot-water outlet, two inches diameter; steam-inlet, two inches diameter; drip-outlet, one inch.

Having now fully described my invention, what I claim, and desire to secure by Letters Patent, is—

1. A water-heater comprising a suitable tank, a plurality of heating-coils extending from top to bottom thereof, an inlet-pipe entering at the top and extending to the bottom of said tank, an outlet-port at the top of said

tank and a thermostat adjacent said outlet, a steam-inlet controlled by said thermostat.

2. A water-heater comprising a suitable tank, a plurality of heating-coils extending from top to bottom thereof, a water-inlet pipe entering near the top and extending substantially to the bottom thereof closely adjacent to said heating-coils, an outlet-port near the top of said tank and a thermostat near said outlet and controlling the supply of steam to the coils.

3. A water-heater comprising a suitable tank, heating-coils extending therethrough, a water-inlet pipe entering at the top, extending close to said heating-coils, and discharging at the bottom of said tank, an outlet-port at the top of said tank and a thermostat extending between the heating-coils and adjacent said outlet-port and controlling the supply of steam to said coils.

In witness whereof I have affixed my name, in the presence of two subscribing witnesses, this the 1st day of July, A. D. 1902.

HENRY S. POWELL.
